UNITED STATES PATENT OFFICE.

JOHN C. FIDDYMENT, OF AKRON, OHIO.

FLUID-EXTRACTING PRESS.

1,333,249.

specification of Letters Patent. Patented Mar. 9, 1920.

Application filed July 24, 1918. Serial No. 246,478.

To all whom it may concern:

Be it known that I, JOHN C. FIDDYMENT, a citizen of the United States, residing at Akron, in the county of Summit and State of Ohio, have invented certain new and useful Improvements in Fluid-Extracting Presses, of which the following is a specification.

This invention relates to an improvement in a fluid extracting press, all substantially 10 as herein set forth and more particularly pointed out in the claims.

In the various forms of presses patented by me heretofore, I have experienced difficulty in effecting a proper escape of the 15 fluid and in holding back the solids. Thus, under extreme pressures, such as required on cotton seed, linseed and similar materials, one difficulty consisted in preventing buckling or displacement of certain parts and in 20 maintaining uniform spaces for the escape of the oil. The solids would also pack in places. The object of the present improvement is to provide an effective arrangement of parts to overcome such difficulties, and to 25 provide a movement which will facilitate the escape of the fluid and prevent the escape openings from clogging, and a further object is to simplify the structure and reduce its cost and upkeep to a minimum.

30 In the accompanying drawing, Figure 1 is a sectional view longitudinally through the shell of the press. Fig. 2 is a cross section of the press on line 2—2, Fig. 1. Fig. 3 is an enlarged view and sectional detail of 35 one of the fluid distributing ducts or channels in the spiral wall of the rotating body. Fig. 4 is a perspective view of one of the division walls used between the baffle members.

In one form of the invention the press 40 comprises a casing or shell —2— cast in one piece or otherwise formed to provide an integral cylindrical inclosure for one or more rotary pressing members. Thus, I may use two rotor members 3 and 4 geared to rotate 45 in opposite directions at the same speed, or I may omit the gearing and modify the construction in other ways without affecting the present improvement. As shown, however, a main feed and presser member 3 is 50 provided with a hollow shaft or integral shaft extensions 5 which are adapted to rotate in bearings in suitable standards 6 and 7, and a second baffle member 4 is mounted on a shaft 8 having bearing in standard 6 and in the wall 9 of shell —2—. The body 55 of rotor member 3 is round and tapered, and

the bore or chamber 10 in shell 2 for rotor member 3 has a slight taper with a flaring exit 11 at one end. This exit may be left open or arranged to be opened or closed, 60 more or less, by a flanged cone-shaped ring 12 secured to the end of shell 2 by bolts and nuts. The material is fed into the shell through a hopper 13 or in any suitable way, and division plates 4' are placed between the 65 notched baffle portion 4 opposite the division wall 15 of member 3.

The rotor member 3 is in effect a screw member in that it is provided over its main length with a spiral thread or flight and a 70 spiral circumferential channel 14 for the material, and the baffles 4 are mounted to rotate in the annular circumferential channel between the annular division walls 15' at the feed end of the press and are slotted to receive the cross connecting portions of the division walls so as to press the material and extract the fluid therefrom during its forced travel forward in the channel. Non-rotatable division plates 4' are also placed between the notched baffle walls 4 directly opposite each annular wall 15' to prevent the drainage openings in such division walls from being uncovered and the solids from passing into said openings. 85

The present invention is distinguished, more particularly, in the means provided for permitting the fluid to escape from the spiral channel 14, regardless of whether one 90 pressing member or two or more are employed. Thus, the annular and spiral division wall or flight 15 forming the channel 14 is made relatively wide and of a diameter to bring its peripheral surface in close proximity to the curved surface of bore 10, and the space allowed may be varied slightly by 95 adjustment of the rotor member longitudinally in the tapered bore 10 so that only the fluid and not the material may escape. The circumferential edge or periphery of division wall 15 is also preferably provided with a peripheral groove 16 to receive the fluid which escapes from channel 14, and the fluid thus gathered up is discharged through a series of tubes 17 extending from said 100 groove and radially in rotor member 3 to a central longitudinal opening 18 therein. This opening 18 has outlet through one or both of the hollow shafts or shaft extensions 5, and the tubes 17 are preferably of tapering or flaring form internally with the 105 larger inner ends open to the main dis-

charge opening 18, thereby providing for a free escape of fluid through the tubes and preventing clogging of the tubes by accumulation of any material which might work its way into them.

The construction of the press is greatly simplified by using a solid shell and forming fluid outlets in the circumferential helical division wall or flights 15 of the rotor member as described, and the escape of the fluid is materially improved and proceeds continuously with an effective exclusion of the material from the fluid passages. The solid or integral shell can be constructed at less expense than a slotted or perforated or sectional shell made of special rings, and it may consist of a cast body with a hardened and relatively thin metal bushing adapted to be replaced when worn out. The size of the escape openings, when accurately determined, are not altered or changed by wear or use of the machine, and the escape of the oil is uniform and constant at all points the full length of the shell. With the present construction it is an easy matter to determine the proper size of opening and maintain the opening to size without any trouble or great expense.

The movement of the material is longitudinally of the shell, and in the rotation of the pressing member 3 the oil follows the groove or channel in the periphery of the flight and each radial opening will carry the oil away while coming constantly opposite all parts of the cake, that is, the material compressed in the channel. The holes or openings through the flights are also made large enough so that all particles escaping from the channels can not clog such openings, and the taper also prevents such clogging.

The machine shown is supported on a base with the rotor member 3 operating in a horizontal plane, that is, on a horizontal axis. However, I wish it to be understood that I may support the shell and screw member in a vertical position and any suitable means may be used to adjust the shell or screw member relatively to each other so that the space between the shell and the flights of the screw may be of uniform size and no unequal wear produced.

In one form of press patented by me I use a conical worm or screw within a divided casing of conical form, and employ a different form of baffle member at the feed end of the press, and in a press of that or kindred type it is not desirable to continue the peripheral channel and make drainage openings in the flights at the feed end of the press. Therefore, I do not limit myself to the use of the drainage openings throughout the full length of the flights as they may be used in only a portion of their length and where most effective.

What I claim is:

1. In a fluid extracting press, a rotor member and a casing member therefor, the said rotor member having circumferential division walls provided with fluid escape ducts opening into the edge of said walls. 70

2. In a fluid extracting press, a shell and a rotor member therein having a longitudinal discharge passage and circumferential division walls provided with fluid escape ducts extending from said passage to the periphery of said walls. 75

3. In a fluid extracting press, a shell, and means for feeding and pressing material placed in said shell, comprising a cylindrical rotor member having a helical wall arranged with its peripheral surface in relatively close working relation to the interior surface of said shell and provided with a longitudinal discharge passage and separate escape ducts extending radially thereof through said wall from its periphery to said longitudinal passage. 80

4. In a fluid extracting press, a shell having a tapering longitudinal bore, and a cylindrical rotor member having a fluid discharge passage longitudinally therein and provided with a helical wall around the same having a peripheral surface corresponding to the taper of the bore, said member having fluid escape ducts radially thereof extending from said passage to the periphery of said wall. 90

5. In a fluid extracting press, a shell and a rotor member therein having a helical division wall provided with a peripheral groove and radial fluid escape ducts open to said groove. 100

6. In a fluid extracting press a shell and a tapering rotor member having an axial discharge passage and a circumferential division wall provided with a peripheral groove and transverse fluid escape ducts connecting said groove and passage. 105

7. In a fluid extracting press, a shell and a rotatable member therein having a circumferential wall providing a spiral channel about the same, said member having a fluid passage longitudinally thereof and a transverse fluid escape passage of flaring form 115 extending through said wall from the periphery thereof to said passage.

8. In a fluid extracting press, a shell, a rotatable member having a circumferential division wall and a longitudinal fluid discharge passage, and separate tubes having flaring bores extending through said member from said discharge passage to the peripheral surface of said wall. 120

9. In a fluid extracting press, a shell having a set of rotary pressing members therein, one of said members having an axial discharge passage for the fluid and a circumferential wall providing a helical channel for the material to be pressed, said wall hav- 125

130

ing a peripheral groove and said member having tubes of internal flaring form extending from said groove to said passage.

10. In a fluid extracting press, a cylindrical shell having a bushing, and a hollow pressure-applying screw rotatably mounted within said bushing with a peripheral edge of the flights of the screw in closely spaced

relation to the internal surface of said bushing, and said flights having a continuous channel therein and escape ducts open to said channel and the interior of said screw.

Signed at Akron, in the county of Summit and State of Ohio, this 13 day of July, 1918.

JOHN C. FIDDYMENT.
